United States Patent

Des. 242,543
Patented Nov. 30, 1976

242,543

COMBINED FIREPLACE HEATER AND GRATE

Walter Russell Betenbaugh, Jr., 4024 Pomfret Lane,
Charlotte, N.C. 28211

Filed July 21, 1975, Ser. No. 597,445

Term of patent 14 years

Int. Cl. D7—08; D23—03

U.S. CL. D23—96

FIG. 1 is a perspective view of a combined fireplace heater and grate showing my new design;

FIG. 2 is an end elevational view taken from the right of FIG. 1;

FIG. 3 is a top plan view thereof; and

FIG. 4 is a front elevational view thereof.

I claim:

The ornamental design for a combined fireplace heater and grate, substantially as shown.
